UNITED STATES PATENT OFFICE

EMRYK DATKA, OF DULUTH, MINNESOTA.

TWYER PEEK-HOLE.

1,360,191.

Specification of Letters Patent. Patented Nov. 23, 1920.

Application filed March 26, 1920. Serial No. 368,951.

To all whom it may concern:

Be it known that I, EMRYK DATKA, a citizen of the United States, residing at Duluth, in the county of St. Louis and State of Minnesota, have invented certain new and useful Improvements in Twyer Peek-Holes, of which the following is a specification, reference being had therein to the accompanying drawing.

10 This invention has reference to twyer sights for blast furnaces and the like, and relates particularly to means for the prevention of the metal parts of the twyer, adjacent the sight or peek hole, being destroyed by the heat of the furnace.

The principal object of the invention is to provide such means which may be readily applied to twyers now in use with as little inconvenience as possible.

20 Other objects and advantages of the peculiar construction will appear as the description thereof proceeds.

In the accompanying drawing forming part of this application and in which like reference characters indicate like parts:

Figure 1 is a side elevation of a common twyer elbow of a furnace shown partly in section, and

Fig. 2 is a front elevation of the peek hole cap or cover common to such twyer elbows.

1 represents the elbow, and 2 the reduced horizontal extension thereupon, through which the interior of the furnace is viewed 35 through the peek hole in the cover or cap 3, which is removably applied thereto. In practice common to such devices the cap 3, which is of metal, is applied directly to the end of the extension 2 and securely held 40 thereupon by suitable bolts and links, not shown, co-operatively engaging with the integral lugs 4 on the cap, and the lugs 5 on the sides of the extension 2.

The cap 3 carries integral therewith a 45 pair of forwardly projecting lugs 6 in which the sight glass is pivotally suspended, the latter not being shown as it forms no part of my present invention.

The invention resides in placing intermediate of the cap 3 and the end of the extension 2, a combination bushing and

washer made of heat resisting substance such as carbon of a composition similar to that used in arc lamps and for electric motor brushes, or the like, the washer portion 55 being shown at 7 and the bushing portion shown at 8. The bushing or central cylindrical portion 8 extends forwardly through the cap 3 and preferably somewhat beyond the outer face of same as shown in Fig. 1. 60

As an additional feature of the invention I provide a bushing 9 which snugly fits within the extension 2 and forms a complete heat resisting lining therefor, the outer end of said bushing being flush with the outer 65 end of the pipe 2, so that the washer portion 7 of the washer and bushing engaged with the cap will contact same. The bushing 9 is preferably of the same material as the washer and bushing.

70 It is well known by those versed in the art that one of the principal difficulties associated with a peek hole of this character is the burning out and destruction of the cap 3 as well as at times the destruction of 75 the extension 2, the prevention of which I have successfully accomplished by the installation of the heat resisting members above described and the application and forms of which may be varied considerably 80 from that illustrated, without departing from the spirit of the invention.

Having thus described my invention, what I claim and desire to secure by Letters Patent is:

85 1. The combination with a twyer peek hole of the character described and cap therefor, of a heat resisting lining within the peek hole and extending entirely through the cap, for the purpose described.

90 2. The combination with a twyer elbow extension and peek hole cap therefor, of a fire-proof member installed intermediate of the extension and the cap and extending centrally through the latter, there being an 95 axially disposed peek hole through the member, substantially as and for the purpose described.

100 3. The combination with a twyer elbow extension and peek hole cap therefor, of a fire-proof bushing within the extension and a fire-proof washer intermediate of the cap

and the extension whereby to prevent excessive heat contacting the walls of the bushing or the peek hole cap.

4. The combination with a twyer peek hole cap or cover, of a combined fire-proof bushing and washer installed intermediate of the cap and the twyer and extending outwardly centrally and beyond the cap for

direct engagement with the glass sight common to such devices.

In testimony whereof I hereunto affix my signature in the presence of two witnesses.

EMRYK DATKA.

Witnesses:
